UNITED STATES PATENT OFFICE.

CHARLES FREBORG, OF KANKAKEE, ILLINOIS, ASSIGNOR TO SCHAEFFER PIANO MFG. COMPANY, A CORPORATION OF ILLINOIS.

PNEUMATIC PIANO-PLAYER.

1,044,639.

Specification of Letters Patent.

Patented Nov. 19, 1912.

Application filed September 21, 1909. Serial No. 518,731.

To all whom it may concern:

Be it known that I, CHARLES FREBORG, a citizen of the United States, residing at Kankakee, in the county of Kankakee and 5 State of Illinois, have invented certain new and useful Improvements in Pneumatic Piano-Players, of which the following is a specification.

The principal object of my invention is 10 to provide a new and improved piano player of the type operating automatically by air pressure.

Another object of my invention is to provide a pneumatic piano player with the little bellows or pneumatics arranged in an 15 advantageous manner.

A further object is to provide a pneumatic piano player that shall have the pneumatics arranged to coöperate advantageously 20 with the piano actions, and so that the parts can be readily assembled and shall be conveniently accessible.

Various other objects will be made apparent in the following specification and 25 claims, taken in connection with the accompanying drawings.

My invention is as broad as the appended claims, but for the purpose of clearly explaining its nature, I have illustrated one 30 specific embodiment in the accompanying drawings, and I now proceed to describe this particular form of my invention in this specification.

Figure 1 is a vertical section showing the 35 general arrangement of the parts of the device. Fig. 2 is a rear elevation of the pneumatics. Fig. 3 is a top plan view of the banks of pneumatics. Figs. 4 and 5 are sections across the banks of pneumatics taken 40 on the lines 4 and 5 in Fig. 3 looking in the direction of the arrows. Figs. 6, 7 and 8 are horizontal sections taken on the correspondingly numbered lines in Fig. 4 looking 45 down. Fig. 9 is a section taken on the line 9—9 in Fig. 4 looking in the direction of the arrow. Fig. 10 is a rear elevation showing a slightly modified form, this view being taken partly in section on the line 10, 10 of Fig. 6. Fig. 11 is a perspective view of the 50 rear face of the board designated 29 in Fig. 10.

The usual cheek blocks of the piano are 55 represented by the reference numeral 15. The key bars 16 are pivotally mounted on the block 17 and carry the usual keys 18 at

one end, and the adjustable studs 19 at the other end, these studs 19 being adapted to engage the lower ends of the stickers or abstracts 20 which actuate the piano action 28.

Each sticker 20 carries a pair of blocks 21 and 22 with which the rod 23 has screw threaded engagement, its top end 24 being modified to receive a wrench, and its lower end carrying a block 25 with a felt pad 26. 65 These blocks 25 are at three different heights corresponding to the heights of the pneumatics. The intermediate blocks are designated as 25' and the lowermost ones by 25''. Each block is engaged by a member 27, 27' 70 or 27'' on a respective pneumatic at the proper height.

The wooden beam or board 29 extends across the width of the piano above the key bars 16, being supported at its ends by the 75 cheek blocks 15. Combined with this beam 29 to form a supporting frame for the pneumatics are the wooden bars 30, 31 and 32. Attached to the under faces of these respective bars or boards are the upper members 80 33, 33' and 33'' of the various banks of pneumatics. The under members of these pneumatics are designated on the drawings respectively as 34, 34' and 34'', and these under members carry the projecting members 85 27 already referred to.

Above the bar 30 is an air chamber 35 in which the usual moderate degree of vacuum is maintained by the main exhausting bellows of the piano player, the conduit which 90 leads to said bellows being indicated in Fig. 3 by the reference numeral 36. The upper wall of the vacuum chamber 35 is the horizontal board 37. Conduits 38, 38' and 38'' extend from the respective pneumatics up 95 through the front wall 29 to the valve chambers 58 in the board 37.

Each valve chamber 58 has an opening 39 above to the outer air and an opening 40 below to the vacuum chamber 35. On the 100 common stem 41 are the respective valves 42 and 43 for the said openings. This valve stem is guided above by the guide 44, and below by the plate 45.

The various conduits leading from the respective openings in the tracker board are indicated by the reference numeral 46. These lead through holes in the block 57 to connecting holes 47 in the block 30. From each hole 47 there is a branch conduit 48 to 110

the respective chamber 49 in the wooden bar 30. Each chamber 49 is closed above by a leather diaphragm 50 surmounted by a button 51 carried on the lower end of the valve stem 41. Also connected to the respective holes 47, which form continuations of the conduits 46, are the thimbles 52 which lead to the supplemental vacuum chamber 53 in the board 56. Each thimble 52 has a disk 10 of celluloid or other suitable material across its end with fine perforations therein, these perforations being the so called "bleed holes." Directly in front of each bleed hole 54 is a stopper 55 of rubber or other 15 suitable material that may be removed when it is desired to gain access to the bleed holes.

In operation, the main bellows maintains a constant degree of moderate vacuum in the chambers 35 and 53. This same vacuum is 20 also communicated through the bleed holes 54 to the ducts 46-47 which lead to the tracker board. Thus it will be seen that the leather diaphragms 50 are subjected to an equal pressure above and below, and hence 25 the valves 42 and 43 stay down by gravity in the position shown in the drawings, closing the openings 40 and connecting the conduits 38, 38' and 38'' to the external air through the openings 39. But when a hole 30 in the music roll coincides with a hole in the tracker board, atmospheric air is admitted to the conduit 46-47 much faster than it can exhaust into the vacuum chamber 53 through the bleed hole 54, and thus the under side of the leather diaphragm 50 is subjected to atmospheric pressure, which raises 35 the button 51, carrying the valves 42 and 43 up so as to close the conduit 38 (or 38' or 38'') to atmospheric air at the opening 39 and to connect this same conduit through 40 the opening 40 and the opening in the plate 45 around the valve stem 41, to the vacuum chamber 35.

The vacuum being communicated to the 45 conduit 38 which connects with the interior of the respective pneumatic, it follows that the atmospheric pressure on the exterior of the pneumatic collapses the same causing the lower member 34 (or 34' or 34'') to rise and 50 by means of the engagement of the projection 27 with the abstract or sticker 20, the piano action is actuated.

The board 30 can be fully equipped with 55 its valves and conduits spaced uniformly along its length so that there will be the required number of valves in the entire width of the piano. It is not necessary that this spacing of the valves on the boards 30 and 37 should be such as to make them register 60 accurately with the abstracts 20. Of course it is necessary that the pneumatics should register accurately with the abstracts 20, but this object can be attained by displacing the pneumatics laterally as much as may be necessary and making laterally extending chan-

nels in the inner face of the vertical board 29, so as to preserve the continuity of the conduits 38, 38' and 38''. These offsets in the conduits are indicated in Figs. 10 and 11 by the reference numerals 62, 62' and 62''.

I desire to call particular attention to the compact arrangement of the banks of pneumatics, also to the arrangement of the same relatively to the casing of the piano. The banks of pneumatics lie close above the rear ends of the piano keys in the vacant space which is found there in the ordinary type of pianos. By my invention I have succeeded in utilizing this space to the highest advantage. It will be seen that the banks of pneumatics lie behind the fall board of the piano and extend only substantially to the same height as the fall board.

One advantage of my device is that all the valves for the pneumatics are on top, although the pneumatics themselves are arranged in three tiers; this makes the valves easily accessible for inspection, repair or adjustments.

I claim:

1. In a device of the character described, a series of pneumatics, a series of respective valves therefor, a supporting board, conduits in the board from the valves to the respective pneumatics, said conduits having offset portions so as to permit the pneumatics to be displaced laterally in order to register with the piano abstracts to which they belong.

2. In a device of the character described, 100 cheek blocks, a board extending in a vertical plane across said cheek blocks, rearwardly projecting boards attached thereto, pneumatics attached to a portion of the number of said rearwardly projecting boards, a 105 vacuum chamber formed between two of said rearwardly projecting boards, and a block attached to the rear edges of the two of said rearwardly projecting boards to form the rear wall of said chamber, conduits in 110 said block leading to the respective openings in the tracker board and also leading through to the front of said first named board and terminating in bleed holes in said front, a vacuum chamber open to said bleed 115 holes, and separate removable plugs in the walls of said chamber for permitting access to said bleed holes.

3. In a device of the character described, 120 cheek blocks, a board extending in a vertical plane across said cheek blocks, rearwardly projecting boards attached thereto, pneumatics attached to a portion of the number of said rearwardly projecting boards, a 125 vacuum chamber formed between two of said rearwardly projecting boards, a block attached to the rear edges of the two of said rearwardly projecting boards to form the rear wall of said chamber, and conduits in the said block communicating with the re- 130

spective openings in the tracker board and leading to channels in the lower wall of said vacuum chamber, said channels leading to the front of said first named board, and 5 means for permitting access to each of said channels independently of the other channels.

4. In a device of the character described, a vacuum chamber, a board forming the under wall of said chamber, separate chambers 10 in said board, diaphragms between said vacuum chamber and said separate chambers, ducts channeled in said board, respec-

tively connected to said separate chambers, and having forward extensions terminating 15 in bleed holes, a vacuum chamber open to said bleed holes, and separate removable plugs in the wall of said vacuum chamber opposite said bleed holes.

In testimony whereof, I have subscribed 20 my name.

CHARLES FREBORG.
